COMBINATION IRONER AND WRINGER

Antoinette W. Zeman, Cleveland, Ohio

Application December 1, 1933, Serial No. 700,460

3 Claims. (Cl. 38—52)

This invention relates to laundry machines and has for its object to provide machines of this character with means whereby one of the rolls as usually employed for a wringing operation 5 may be conveniently removed and replaced by a roll suitable for an ironing operation, and whereby the latter roll may be in turn interchanged with the former roll for a subsequent wringing operation.

Some power-driven domestic laundering machines have, in combination with the washing mechanism, a power driven set of wringer rolls. These are generally mounted in a frame, which in turn is mounted on a vertical shaft attached 10 to the side of the washing machine, power to the rolls being transmitted by means of this shaft. Until a short while ago, most of these wringer frames were permanently attached to the driving shaft of the washing machine; and separate 15 machines were sold for use in ironing the clothing.

Recently, there have appeared on the market machines in which the entire wringer frame could be detached from the vertical shaft; and 20 provision is made on these machines for fixing on the shaft an electrical ironing machine. This type of machine has a decided economy over the old type, in that only one power drive need be purchased for washer, wringer and ironer; but it 25 has several disadvantages. The necessary weight of the wringer and ironer mechanisms, complete with their frames, makes the change a difficult task for the average housewife or laundress; and the ironing must be done at wringing level (above 30 the wash machine wash-tubs), necessitating the use of a high stool, unless the operator desires to work standing up.

With the view of eliminating these disadvantages, I have prepared a machine which can be 35 converted from a wringer to an ironer merely by changing a single roll, the driving roll being used both as a wringing and an ironing roll. I have furthermore so designed my machine that the frame carrying my rolls is vertically adjustable, permitting the operator to iron at any desired level within the capacity of the machine. The roller frame has the further advantage of being open at one end at least, so that fancy ironing 40 may be done successfully.

A preferred form of my invention is shown in the accompanying drawings, in which

Figure 1 is a side view of my improved ironer and wringer shown as being attached to a side 45 of a wash tub of a washing machine.

Figure 2 is a top view of the same machine, with the upper shaft bearing removed.

Figure 3 is an end view of the upper part of Fig. 1.

Figure 4 is a section taken on line 4—4 in Fig. 1, showing a journal in formed condition and the cam holding it so.

Figure 5 is a section along the lines 5—5 in Figure 1, showing the casing and its bearing and the shaft therein.

Figure 6 is a section along the lines 6—6 in Figure 1, showing one kind of a brush and the mechanism for conveying electric current for heating the ironing roll.

Figure 7 is a partial view of the ironer and 15 wringer frame, partly in section showing the mechanism for relating the roll frame to the casing.

Figure 8 is a side view of the roll-frame, on a larger scale, partly in section, and shows one of 20 the roll journal bearings as being open or deformed and a roll as being tilted for insertion and removal thereof and also shows the cams on the handle for forming of the journal bearing and for permitting deforming thereof.

Figure 9 is a perspective view of the tiltable, grooved roll.

Figure 10 is a perspective view of a tiltable, cloth covered roll.

Figure 11 is a fragmental section along the 30 line 11—11 of Figure 1.

Figure 12 is a fragmental view of the lower part of the casing, partly in section to show the lower end of the casing engaging in the collar more clearly.

Figure 13 is a transverse section along the line 35 13—13 of Figure 1 showing connection of the casing and roll-frame and the roller drive means.

Referring to the drawings, I weld or otherwise secure to the bottom of the tub portion of a 40 washtub (1) a bearing bracket and gear housing (2) the top portion of which is in the form of a cylindrical collar (3). A cylindrical casing (4) is centralized in the collar, which acts as a bearing and an endwise abutment for the 45 lower end of the casing. At the top of the tub, in vertical alignment with the collar (3) is a support or bearing bracket (5). A split collar bearing (6—6') is riveted or welded to the support; the casing has a diametrically reduced portion (7) which fits this bearing. On assembling the machine, the casing is fitted into the collar (3), and the bearing (6—6') is then affixed to the support (5) at the diametrically reduced 50 portion. An opening (8) extends the entire 55

length of the casing from the bottom bearing up. In the portion (7) of the casing are indentations (9); a peg (10) connected to a handle (11) is normally kept in an indentation by the pressure 5 of a spring (12). The casing may thus be rotated after unlocking, by pulling on the handle. The position of the indentations fixes the angles at which the casing may be locked in position for wringing.

10 In the bottom of the housing (2) is a bearing (13) in which the shaft (14) rotates. This shaft is provided with a journal in the bearing (15) at the top of the casing. It is driven by gearing (16) driven by a power shaft (17) connected to 15 the washing machine motor; or it may be driven by any suitable driving mechanism. The shaft (14) has gear teeth cut therein extending from the lower bearings (3) and up beyond the bearing (5) meshing into the below described gears. 20 A roll-frame (18) is mounted on the casing (4). For the purpose of adjustably and yet rigidly mounting this frame, vertically aligned indentations (19) are provided in the casing, and bolts (20) operated by thumb screws (21) lock the 25 frame in any desired vertical setting, thus permitting of ironing at any desired height. In the upper portion of the roller frame is fixedly mounted a stainless steel roll (22) fixed in bearings (23). Gearing (24) connects the roll to the 30 shaft (14). Removable plates such as the plate (25) shown are provided about the gearing to permit of inspection and servicing.

In the roll (22) are three electric heating elements (26), (261), and (262) of any conventional 35 design electrically insulated from the roll. Each of the heating elements has one end of its winding connected to the common lead line (263) which is connected to the collector ring (27) having the brush (28) bearing thereon and being 40 connected to the line (281) forming a part of the circuit of a source of electricity. Each of the heating elements has the other end of its winding connected to individual lead lines. Line (264) leads from the element (262) to the 45 collector ring (29) which is contacted by the brush (291) connected to the line (292) forming a part of the electric circuit of the source of electricity and the switch (302) is interposed in the line between the collector ring (29) and the line (292). 50 Line (265) leads from the element (261) to the collector ring (294) contacted by the brush (295) connected to the line (292) with the switch (301) interposed in the connecting line. Line (266) leads from the element (26) to the collector ring 55 (267) contacted by the brush (268) connected to the line (292) with the switch (300) interposed in the connecting line.

With this line and switch arrangement, any 60 one of the heating elements can be switched in or out individually to heat the element as desired with most heat produced at either end of the roll or at the middle. Various combinations of heat production in the roll can be effected by this switch arrangement. The collector ring and 65 switch arrangement shown in Fig. 6 or any other convenient structure, may be used for leading electric current to and from the heating elements. Electric current may be brought to the switches by an ordinary electric cable connected to an 70 electrical outlet, or, if desired, be connected to the same source of electricity which drives the washing machine.

The lower portion of the frame is separated 75 from the upper portion, leaving an opening (32) to permit of fancy ironing. Interchangeable rolls

(33) and (33'), one preferably of compressible rubber and corrugated on the outer surface thereof and being a wringer roll, another similar roll, preferably of incompressible material, and being an ironer roll, have diametrically reduced 5 ends (34) journaled in bearings mounted on the roll-frame as shown and have the shoulder (341) to prevent endwise movement of the roll when the journal is assembled. Each of these bearings is shown as composed of two parts (35 and 36) the 10 latter parts being movable to form and to deform the journal bearings therein for insertion and removal and exchange of the rolls (33) and (33').

The springs (37) abut the corresponding bearing parts (36) and, when compressed, keep the 15 bearings in journal forming condition. The keeper plates (38) abut the corresponding springs (37) and are abutted by the cams (40) on the ends of the levers or arms (39) which are pivoted on the roll-frame by the pivot bolts (41) and are 20 lengthwise adjustable by means of slots 42 through which the bolts extend, being secured in their adjusted positions by means of the thumb screws (43). The normal pressure between the 25 rolls (22 and 33) may be varied by varying the position of the pivot bolts (41).

The handle (44) pivoted to both arms (39) by means of the pins (45) acts as a means for manually releasing the springs and the parts (36) of the bearings for deforming the journal bearings 30 therein and, for forming the journal bearings upon corresponding axial movement of the handle (44). This deforming of the bearings permits either of the rolls (33) and (33') to be 35 tilted for insertion or removal thereof.

The bracket (46) has one end thereof journaled on the shaft (14) and the other end thereof is forked to straddle the shaft of the roll (22) and abut the outer end of the upper bevel gear (24) to keep the latter in mesh with its co-driving 40 bevel gear. The forked part of the bracket (46) as well as the journal part thereof may be made integral with the roll frame (18).

The springs (37) are of wide range of activity so that the bearing parts (36) can be moved a 45 considerable distance for release and insertion of the roll (33). The cam tops (40) need not be of large eccentricity since the same are used only for final location of the bearing parts (36). For separating the bearing parts (35) and (36) the 50 bolts (41) and the levers (39) are first released as seen in Fig. 8 with the levers pulled way back. The roll (33) is then tilted whereby the bearing parts (36) are moved away from the bearing parts (35) and this moving is continued manually 55 until the bearing is sufficiently separated to move the roll (33) endwise and tilt the same for removal thereof. After the roll (33') is inserted, the levers (39) are pushed inwardly to form its bearing, the bolts (41) are then tightened slightly, the 60 levers (39) are then moved to the position shown in Fig. 1, the bolts (41) are then further tightened and the levers (39) moved a little further to cause the cam to lock the bearing parts (35 and 36) for journal forming.

When the machine is to be used as a wringer, the rubber roll (33) is used, and no heat is applied to the roll (22). As the frame (18) can be rotated, and locked in a series of positions, the device can be used for wringing in any desired 70 position above the tub level, in a manner similar to the wringers commonly in use at present. The wringing is done between the upper stainless steel roll, and the lower rubber roll; because of the springs (37) and the normal pressure adjust- 75

ment, the use of the steel roll does not cause undue breakage of buttons, etc., as would be the case with rigid rolls.

When ironing is to be done by the device, the handle (44) is shifted, and the cloth covered ironing roll (33') replaces the rubber roll. The ironer is now vertically adjusted to any position permitted by the indentations (19). The heat may be turned on to any desired degree by the switches (30). By regulating the heat in the heated roll, the ironing may be accommodated to different types of laundry. The normal pressure between the rolls, which may be varied by varying the compression of the springs (31), determines the arc of contact (caused by the flattening of a part of the cloth roll); this has a very definite bearing on the amount of ironing done, and is another method of control which may be used by the operator.

It is apparent that this combination is much more economical than the machines now in use; only one additional roll, and some wiring, is needed to add the ironer feature to the combination of laundering machines of the past art.

While I have disclosed a preferred form of my invention, substitution of mechanical equivalents for the connecting gearing, and other common mechanisms shown in the drawings, and of various heating devices for the roll (22) are to be considered within the scope of this invention.

Having described my invention, what I claim is:

1. A laundering machine including a roll-frame, journal bearings mounted at opposite ends of said roll-frame, laundering rolls journaled in said bearings, the bearings for one of said rolls being each composed of separable parts, a spring abutting one part of each of said bearings, a plate abutting each of said springs, a cam abutting each of said plates, and operatively connected to said cams and a handle mounted on said roll-frame and being movable in one direction to permit separation of said parts and in the opposite direction for operating said cams to reassemble the journal bearings. 5

2. A laundering machine including a roll-frame, journal bearings mounted at opposite ends 15 of said roll-frame, laundering rolls journaled in said bearings, the bearings for one of said rolls being each composed of separable parts, a spring abutting one part of each of said bearings, a plate abutting each of said springs, a cam abutting each of said plates, and a handle connected to each of said cams and pivotally mounted on said roll-frame and being movable in one direction to permit separation of said parts and in the opposite direction to reassemble the journal 20 bearings, each of said arms being longitudinally adjustable with respect to its pivotal mounting. 25

3. In the combination recited in claim 2, a handle common to and connecting the said arms. 30

ANTOINETTE W. ZEMAN.
